UNITED STATES PATENT OFFICE.

JOHN AUSTIN VICTOREEN, OF CLEVELAND, OHIO.

RADIOFREQUENCY APPARATUS.

Application filed April 30, 1926. Serial No. 105,890.

My invention relates to radiofrequency apparatus and relates particularly to such high frequency tuning apparatus comprising an electrical coil of substantially constant inductance to a given high frequency current and a condenser adapted to be adjusted so as to vary its electrical capacity, associated therewith.

More particularly my invention relates to tuned high frequency transformers and is particularly applicable for use in radio systems in high frequency amplifying circuits and is particularly applicable to such systems employing radio frequency amplifiers of constant frequency.

An object of the present invention is to provide for radio systems, an improved transforming apparatus comprising an inductance coil and a variable condenser so constructed as to be capable of being inexpensively manufactured as a unit and which permits approximate tuning to the frequency of current in the system by adjustment of the variable condenser portion thereof.

Another object of my invention is to provide a transforming unit as aforesaid in a casing containing the inductance and capacity components and in which the electrical constants of the components may be varied by adjustable movement.

Another object is to construct a device for the coupling of vacuum tubes and their associated circuits which will effectively prevent self-sustained oscillation of the tubes and their circuits.

Another object is to provide a device of the class described including inductance and capacity components in which the reactance-resistance ratio may be varied by moving a conductor in adjustable relation thereto.

Other objects of my invention and the invention itself will become apparent as the following description of an embodiment of my invention progresses, and in which description reference will be had to the drawings accompanying this specification and which are a part thereof.

Referring now to the drawings,—

Fig. 1 shows a side elevation of an embodiment of my invention, a portion of the outer casing thereof being shown as broken away to expose certain of the inner parts.

Fig. 2 shows a section taken on the line 2—2 of Fig. 3.

Fig. 3 shows an end view of the embodiment of Fig. 1.

Fig. 4 shows a section taken on line 4—4 of Fig. 3.

Fig. 5 shows a plan view of the condenser portion of the apparatus.

Fig. 6 shows an end view of the condenser portion.

Fig. 7 shows a portion of a typical electrical circuit in which the apparatus of my invention may be employed.

Figs. 8 and 9 show a modified form of my invention, Fig. 9 being taken on line 9—9 of Fig. 8.

Referring now to the different figures of the drawings in all of which like parts are designated by like reference characters, at 1 is shown a cylindrical casing having end walls 2 and 3, the end walls being clamped onto the ends of the cylindrical casing portion by a threaded rod 4 and clamping nuts 5 and 6 on each end of the rod.

The cylindrical casing 1 is positioned with reference to the end walls 2 and 3 by flanges 7 and 8 on the end walls and projecting therefrom as shown. The end walls 2 and 3 are centrally perforated to admit the bolt 4.

At 9 and 10 I show a pair of electrical coil windings or inductances carried on bobbins 11 and 12, respectively, the winding 9 being preferably the primary winding of an electrical transformer for high frequency currents and the winding 10 being the secondary of such transformer, the bobbins 11 and 12 carrying the windings aforesaid of preferably an axial bore, the threaded rod 4 passing through the bore of each coil bobbin which is secured on the rod by means of a pair of nuts 13 and 14 threaded onto the rod 4 and clamping the bobbins between them.

At 16, 17 and 18 I show metallic sheets perforated centrally, the first two of these sheets being concavo-convex and oppositely disposed with their concave sides facing each other and the sheet 18 being disposed intermediate the concave sheets 16 and 17 and insulated therefrom by insulating discs 19 and 20 of mica or other insulating material. The intermediate metallic sheet 18

may be, and preferably is, shown in the form of a disc as may be also the sheets 16 and 17, which, however, are shown as being, in the embodiment illustrated, rectangular in form.

The metallic sheets 16 and 17 in the embodiment illustrated are in electrical contact with the nuts 14 and 21 and perhaps also with the rod 4 on which the nuts 14 and 21 are carried, whereas the metallic plate 18 has a central opening 22 of larger diameter than the diameter of the rod 4 and is insulated from the rod 4, the two plates 16 and 17, and the plate 18 forming the condenser. The two plates 16 and 17 are electrically connected to the two terminals of the electrical winding 10, connection being made preferably to the conductor plate 18 by a soldered connection at the periphery of the plate 18 with a circuit conducting wire 23, a tap 24 leading therefrom to the outside terminal of the winding 10, the inside terminal being connected by a tap 25 to the nut 14 and thence through the rod 4. The capacity of the condenser is varied by turning the nut 21 on the rod 4 to compress or to restore from compression the concave-convex plates 16 and 17 so as to vary the mean effective distance between the plates 16 and 17 and the intermediate plate 18 over their entire area. Binding post terminals 26, 27, 28 and 29 are provided being carried on the end wall 2 which is made of insulating material, there being circuit conductors such as the circuit conductors 30 and 31 leading from the terminals of the windings 9 and 10 to connect these windings to the binding posts. It is understood that a pair of the binding posts such as the binding posts 26 and 27 will be connected to the winding 9, and a pair of binding posts such as the binding posts 28 and 29 will be connected to the winding 10, there being also connected the two conductors of the condenser to the latter two binding posts.

Referring now to the circuit diagram of Fig. 7 showing a portion of a radio circuit in which my invention may be used, at 13 is shown the primary winding of the transformer and at 14 the secondary thereof, each comprising a large number of turns of wire, the exact number of turns, however, being variable and depending largely upon the frequency of alternating current adapted to traverse the windings. When the apparatus of my invention is applied to the better known forms of radio-amplifying systems now in use I have found that I secure very good results using for the winding 9, 200 turns of wire, and for the winding 10, 300 turns of wire.

When using such windings the efficiency of the circuit is increased considerably by connecting the condenser electrode in multiple across the 300 turn coil, since the dis-

tributed capacity in the coil is insufficient to completely balance the inductance thereof to the frequency of current commonly employed in such systems; the capacity of the added variable condenser is sufficient to make the electrostatic capacity of the apparatus more nearly balance the distributed capacity thereof, to approximate the resonant condition.

The windings 9 and 10 being placed in the circuit of Fig. 7, as shown, and the variable condenser comprising the conductor plates 16 and 17, and 18, being indicated at 30, the terminals 31 and 32 represent the input terminals of the apparatus and the terminals 33 and 34 represent the output terminals of the apparatus, the latter leading to the audion amplifying tube 35, which has associated therewith a filament energizing battery A and an amplifying battery B according to the usual practice.

At 36 I show the output terminals for the complete apparatus comprising the apparatus of my invention associated with the audion tube and energizing batteries.

The apparatus of my invention is especially adapted to be inserted in the amplifying units such as shown in Fig. 7 of a radio-frequency amplifying system. The apparatus of my invention comprises a transformer having a resonant curve which is many times sharper than the other types of transformers commonly employed. By making the resonant curve of great sharpness selectivity is accomplished and moreover the use of an aperiodic primary coil is possible.

My device prevents self sustained oscillations in the vacuum tubes and their associated circuits, because, I believe, of the combination of a transformer and a suitable conductor suitably disposed in the field thereof, for example, as described and as shown by the drawings, but I have found that the use of an aperiodic primary coil for the transformer also in part prevents such oscillations and thereby renders the system more stable. However, whether the primary coil or inductance be aperiodic or not, the device described and shown permits the potentiometer such as 40 to be used solely as a volume control and not as a losser.

The conductor 16, being aperiodic due to its shape, and disposed so as to cut a portion of the field of the transformer as shown, acts to dampen the circuit and to reduce greatly the inductance of the transformer, thereby changing the ratio of reactance to resistance and due to its relatively low resistance causing any losses to be sustained in the internal circuit comprising the transformer rather than in the external circuit comprising the conductor. It may be, however, that very little loss is 130

actually so sustained but that the prevention of self sustained oscillations is attained by the setting up of counter forces in the inductance and its circuits due to the low 5 resistance of the conductor as compared with that of the inductance and its circuits.

In Figs. 8 and 9 I have shown a device resembling in operation the device of Figs. 1 to 6 but differing therefrom in certain 10 structural respects. These figures show a casing 1, end walls 2 and 3, threaded rod 4 and clamping nuts 5 and 6 thereon as shown in Figs. 1 to 6. In place of the bobbins 11 and 12, I show a bobbin 41 having spaces 15 for primary and secondary inductances or coils 42 and 43 respectively, the bobbin being shown as composed of assembled discs of insulating material on certain of which discs 44 the wire is wound between the other 20 discs 45. The coils 42 and 43 are thus assembled with their axial openings in alignment.

A plurality of aperiodic conductors of 25 relatively low resistance are assembled at the end of the coils. As shown there are two such conductors 46 in the form of brass plates or sheets each perforated near its edge as at 48 to pass onto rod 4 where they are clamped in rotatably adjustable position 30 and are adjustable toward and away from the coils as by nuts 49 and 49^a. Shims (not shown) may be used with either or both nuts 49 and 49^a or the plates 46 may be bent to suitably adjust their position in the field 35 of the windings or coils. These plates extend across the axial openings or air cores of the coils and may be rotated into various positions as indicated by the full and dotted lines in Fig. 9.

40 Nut 49 also serves to fix the position of the bobbin on the rod 4. An additional nut 49^b engages the condenser plate 16 and in conjunction with nut 21 serves to adjust the position of the condenser on rod 4. Such 45 adjustment of the condenser relative to the bobbin and coils may be desirable to obtain the correct amount of change in the reactance-resistance ratio of the inductance when the conductors 46 are omitted, since 50 the brass plate 16 then performs the functions of the conductor 46 in addition to its functions as a plate of the condenser.

In either case, however, the self-sustained 55 oscillations of the tubes and their circuits are prevented and the desired reactance-resistance ratio of the inductances is obtained when the conductor (either plates 46, or plate 16) is of suitable size and is suitably disposed in the field of the inductance.

60 In Figs. 1 to 6 the plate 16 is shown of a size suitable for accomplishing the desired purposes when disposed in the field as shown, nut 4 having been selected after experiment to insure a clearance between the 65 transformer coils and plate 16 which is suit-

able for the desired purposes. In Figs. 8 and 9 the effective size of conductors 46 may be adjusted thereby obtaining the desired results or, when plates 46 are omitted, the plate 16 may be brought into the suitable position with respect to the coils by 70 nuts 49^a and 21.

The condenser comprising plates 16 to 21 inclusive is substantially the same in construction and manipulation as the corresponding condenser of Figs. 1 to 6.

It will be evident to those skilled in the art that I have provided apparatus possessing many desirable properties and characteristics. By means of my invention I am 80 enabled to manufacture on a commercial scale ratio frequency apparatus each comprising a self-contained inductance and a condenser, tuned at the factory and fixed to operate at a predetermined frequency. 85 Moreover, each apparatus is so constructed that self-sustained oscillations in the circuit are prevented. An additional feature of my invention is that tubes having different internal capacities may be employed with the apparatus without appreciably affecting the resonant frequency of the apparatus. In other words, an apparatus embodying my invention and comprising a given inductance and condenser tuned to a determined frequency may be employed without appreciable effect on the resonant frequency with tubes having relatively widely varying internal capacities.

90 It will be understood from the foregoing 100 description and the drawings that the condenser employed is of a sufficient capacity so that its range of adjustment is sufficient to cover reasonable differences in inductance, due to manufacturing tolerances in the windings of the inductance. It will also be understood that the conductor or condenser shown and described herein and to be employed as a dampener of oscillation is of a 105 sufficient size to exert the desired amount of damping on the circuit of which the inductance is a part.

The conductor 16, or conductors 46, act to 110 change the reactance-resistance ratio of and dampen the inductance and its circuits to the extent of preventing self-sustained oscillations of the vacuum tube and its circuit, but this change and damping is not carried on to the extent of undesirably affecting or impairing the resonant characteristics of the 115 tube and its circuit. Moreover the action of such conductor is to set up counter forces which, due to the relatively low resistance of the conductor, are almost equal to the applied forces, and as a result the circuit contains only sufficient excess of positive resistance to insure stability.

120 This application is a continuation in part of my copending application, Serial No. 727,853, filed July 24th, 1924.

Although I have disclosed in this application my inventions of method as well as apparatus I am presenting claims in this application directed to the apparatus, and am presenting claims to the method in my co-pending application Serial No. 105,881, filed April 30, 1926.

I claim:

1. In apparatus of the class described, the combination with an enclosing casing, of a pair of bobbins disposed in axial alignment within the casing, a rod having a threaded end, said bobbins being telescoped over said rod, the said threaded end of the said rod projecting beyond the bobbins, a pair of suitable condenser plates disposed in tube oscillation preventing position in the field of the windings on the bobbins and co-axially of the rod, a threaded nut reciprocable on the threaded end of the rod and adapted to flex one of said condenser plates to vary the electrostatic capacity between the plates, a pair of end walls for the casing, said rod being rigidly secured to one of said end walls and supporting the other end wall, transformer windings on the bobbins and electrical circuit connections connecting the condenser plates in multiple with one of said transformer windings.
2. In apparatus of the class described, the combination with an enclosing casing, bobbins disposed in axial alignment within the casing, a rod having a threaded end, said bobbins being telescoped over said rod, the said threaded end of the said rod projecting beyond the bobbins, a pair of suitable condenser plates disposed in tube oscillation preventing position in the field of the windings on the bobbins and co-axially of the rod, one of said plates being of concavo-convex form and of inherent resilient metallic material, a threaded nut reciprocable on the threaded end of the rod and adapted to "flatten" said concavo-convex condenser plates to vary the electrostatic capacity between the plates, a pair of end walls for the casing, said rod being rigidly secured to one of said end walls and supporting the other end wall, transformer windings on the bobbins and electrical circuit connections connecting the condenser plates in multiple with one of said transformer windings.
3. In apparatus of the class described, the combination with an enclosing casing, bobbins disposed in axial alignment within the casing, a rod having a threaded end, said bobbins being telescoped over said rod, the said threaded end of the said rod projecting beyond the bobbins, a plurality of suitable condenser plates disposed in tube oscillation preventing position in the field of the windings on the bobbins and co-axially of the rod, two of said plates being concavo-convex resilient metallic plates, and an intermediate plate being insulated from the

other said plates, a threaded nut reciprocable on the threaded end of the rod and adapted to "flatten" said concavo-convex condenser plates to vary the mean effective distance between the concavo-convex plates and the intermediate plate, a pair of end walls for the casing, said rod rigidly securing the said end walls to the side walls of the casing, transformer windings on the bobbins, electrical circuit connections connecting the condenser plates in multiple with one of said transformer windings.

4. In a transforming unit for radio frequency amplifiers of constant frequency, the combination with a pair of transformer windings axially disposed with reference to each other, one of the said windings being an aperiodic primary winding and the other winding being a secondary winding, a casing enclosing the said winding and supporting the same, a variable condenser secured within the casing and disposed axially and in tube oscillation preventing position in the field of the winding, said condenser comprising a pair of oppositely dished metallic plates and an intermediate plate insulated therefrom, and variably adjustable means adapted to variably flex the dished plates to vary the electrostatic capacity between the plates.

5. In a transforming unit for radio frequency amplifiers, the combination with a pair of transformer windings each having an air core axially aligned with reference to each other, a suitable variable condenser disposed axially of the windings at a predetermined tube oscillation preventing position within the field thereof and extending across the said air core, the condenser being adjustable to vary the electrostatic capacity thereof, and a casing, housing and supporting the said windings and condenser.

6. In a transforming unit for radio frequency amplifiers, the combination with a pair of transformer windings in inductive relation to one another and having air cores, of a suitable variable condenser disposed in tube oscillation preventing position in the field of the winding and extending across one of the cores, the condenser being adjustable toward and away from one of the windings, the condenser also being adjustable to vary its electrostatic capacity.

7. In a transforming unit for radio amplifiers, the combination with a pair of aligned transformer windings in inductive relation to one another, of a suitable conductor of such area and size as to be capable of preventing tube oscillation disposed in tube oscillation preventing position in the field of the windings and of such low resistance as compared with that of the windings as to keep resistance losses at a minimum.

8. In a transforming unit for radio am-

- plifiers, the combination with a pair of transformer windings in inductive relation to one another, of a suitable conductor of such area and size as to be capable of preventing tube oscillation disposed in a position in the field predetermined for the prevention of self-sustained oscillations in the windings, and of such low resistance as compared with that of the windings as to keep resistance losses at a minimum.
9. In a transforming unit for radio amplifiers, the combination with a pair of transformer windings in inductive relation to one another, of a suitable conductor composed of a plurality of parts disposed in tube oscillation preventing position in the field of the windings and adjustable to vary the effective area of the conductor.
10. In a transforming unit for radio amplifiers, the combination with a pair of transformer windings in inductive relation to one another, of a suitable conductor composed of a plurality of parts disposed in tube oscillation preventing position in the field of the windings and adjustable to vary the effective area of the conductor, the con-
- ductor being adjustable toward and away from the windings.
11. In a transforming unit for radio amplifiers, the combination with a pair of transformer windings in inductive relation to one another, of a suitable conductor composed of a plurality of parts disposed in tube oscillation preventing position in the field of the windings and adjustable to vary the effective area of the conductor, and a variable condenser disposed adjacent to the windings and adjustable to vary its electrostatic capacity.
12. In a transforming unit for radio amplifiers, the combination with a pair of aligned transformer windings in inductive relation to one another, of a suitable conductor adjustably disposed in tube oscillation preventing position in the field of the windings, and a variable condenser disposed adjacent to the windings and adjustable to vary its electrostatic capacity.

In testimony whereof I hereunto affix my signature this 29th day of April, 1926.

JOHN AUSTIN VICTOREEN.
